(57) **CLAIM**

The ornamental design for an LED optical component, as shown and described.

DESCRIPTION

FIG. 1 is a front/top perspective view of an LED optical component according to the invention;

FIG. 2 is a front/bottom perspective view of the LED optical component of FIG. 1;

FIG. 3 is a rear/top perspective view of the LED optical component of FIG. 1;

FIG. 4 is a rear/bottom perspective view of the LED optical component of FIG. 1;

FIG. 5 is a top plan view of the LED optical component of FIG. 1;

FIG. 6 is a front elevational view of the LED optical component of FIG. 1;

FIG. 7 is a bottom plan view of the LED optical component of FIG. 1;

FIG. 8 is a left side elevational view of the LED optical component of FIG. 1;

FIG. 9 is a right side elevational view of the LED optical component of FIG. 1;

FIG. 10 is a rear elevational view of the LED optical component of FIG. 1;

FIG. 11 is a cross-sectional view of the LED optical component of FIG. 1 taken along line 11-11 in FIG. 10;

FIG. 12 is a cross-sectional view of the LED optical component of FIG. 1 taken along line 12-12 in FIG. 10; and,

FIG. 13 is a cross-sectional view of the LED optical component of FIG. 1 taken along line 13-13 in FIG. 10.

The broken lines illustrating portions of the LED optical component form no part of the claimed design.
